AUTOMATIC VOCAL ANNOUNCEMENT
SELECTOR

Orville K. Barnes, Jr., Portsmouth, Ohio, assignor
of thirty-one per cent to Theodore Vournazos,
twenty-five per cent to Herbert Major and ten
per cent to Laurence M. Kimble, all of Ports-
mouth, Ohio

Application December 13, 1939, Serial No. 309,093

11 Claims. (Cl. 274—18)

The present invention is concerned with an automatic vocal announcement selector. It is particularly adapted for use in connection with voice reproduction for talking scales, weighing and measuring devices, annunciator systems and the like.

It is an object of the invention to provide means whereby a series of several hundred weight announcements may be placed on a single record and the desired announcement picked out and reproduced in response to a specific signal such as weight on a scales or the like.

It may be seen that such a device readily lends itself to use where people open doors, operate hidden switches in any way instead of utilizing weight as a prime motivator.

The device could be operated by an electric motor the circuit of which is controlled by desired signals.

Again, the invention can be utilized in connection with such signal means as a photo-electric cell, general light sensitive type or one which responds to specific colors, and electric circuits which may be effected by body capacity. This in itself could be used as a means for selecting the different announcements. For example, different advertising announcements could be made to people wearing different colored suits, people of different heights and the like. Or various announcements could be made to people entering certain rooms such as the class of goods carried by the department stores, directions where certain things may be found, time and weather reports as well as advertising of a somewhat spectacular character in general.

It is an object of the invention to provide a mechanical means for storing up energy of an intermittent nature to be delivered in measured quantities at a later time to operate such a device.

Other objects of the invention will appear in the following detailed specification and in the claims.

In the drawings:

Fig. 1 is a perspective assembly view of the device.

Fig. 2 is a plan view thereof.

Fig. 3 is an end view of the spring motor and other detail.

Fig. 4 is an end view of the toggle detail.

Fig. 5 is an end view of the device showing the cam and locking control.

Fig. 6 is an enlarged detail of a control plate.

Fig. 7 is an enlarged fragmentary elevation of a portion of the control mechanism.

Fig. 8 is a fragmentary end elevation of a portion of the drive mechanism.

Like numbers refer to like parts throughout.

Referring to the drawings, a grooved cylinder 1 or record 1 is provided, which has a series of sound tracks thereon in side by side relation. Where the device is made part of a scale having a range up to three hundred pounds, two hundred and seventy announcements would be sufficient since the very few weights under thirty pounds would be measured. The scale referred to is of the well known conventional type having a platform upon which the person to be weighed stands. As is well known in the art the platform is connected by levers with a dial which indicates the weight of the person standing on the platform. The platform itself moves somewhat under the effect of the weight of the person standing thereon. Of course advertising could be combined with the weight announcement or other information could be given and fortunes could be told.

Record 1 is carried by cylinder 2 which is mounted for rotation on shaft 3 by means of spokes 4 and hub 5. Shaft 3 is journaled in up-standing side wall members 6 and 7 by means of roller bearings 8 and 9.

The announcements are picked up from the sound tracks on record 1 by reproducer 10 which may be the regular mechanical phonograph head or an electrical pick up.

Reproducer 10 is carried by curved supporting arm 11 which is hinged at 12 to mounting block 13. Extending from the reproducer 10 is flexible sound carrying tubing 14 leading to the standard phonograph horn if mechanical equipment is used instead of an electrical pick-up. A loud speaker may of course be used.

Mounting block 13 slides on fixed guide bar 15 which is supported by side members 6 and 7 and extends between the two. The opposite end of arm 11 is supported by mounting block 16 which slides on movable guide bar 17.

Mounting block 13 is threaded internally so as to mate with threaded selecting shaft 18 which places the reproducer 10 at the desired announcement on record 1. As shaft 18 rotates it causes block 13 to slide on guide bars 15 and 17. Shaft 18 is supported in side members 6 and 7 by roller bearings 19 and 20 and extends through bearing 21 in upright member 22.

On the end of shaft 18 adjacent bearing 21 is mounted a worm 23 which mates with worm gear 24 mounted on vertical shaft 25 supported by member 22.

At the bottom of shaft 25 is worm gear 26 which mates with worm 27 mounted on horizontal drive shaft 28. Drive shaft 28 is mounted at one end in a bearing in the lower part of member 22 and at the other extends through bearing support 29.

Drive shaft 28 is connected by suitable means to the platform of a scale which is depressed by an amount depending on the weight placed thereon. Any means can be used to rotate shaft 28 a definite predetermined amount in response to a certain predetermined stimulus or force.

This invention is not confined to weighing machines but may include any signal in response to which a certain announcement is desired to be made.

Any turning of shaft 28 alters the position of reproducer 10 on record 1 in a corresponding manner so that the proper announcement may be made in accord with the signal or impulse initiating the rotation of shaft 28.

The opposite end of selector shaft 18 extends through side wall 7 and has locking gear 30 keyed thereto. A locking pin 31 is slidably mounted in guide mounting 32. Locking gear or wheel 30 has a slot or tooth for each announcement and locking pin 31 engages the proper slot or space between the teeth before the pickup stylus on reproducer 10 or pickup 10 touches the selected sound groove.

Bent lever 34 is pivoted to the outer face of side member 7 at 35 and has an enlarged cam portion 36. Spring 33 urges pin 31 to ride on cam portion 36.

Bell crank 37 is mounted on one end of rod 139 which is journaled in side members 6 and 7. The short arm of crank 37 carries one end of guide bar 17.

Firmly attached to the end of shaft 3 which passes through side member 7 is cam 38 which rotates with shaft 3. Cam follower 39 has a square portion 41 slidably mounted in guide block 40. The upper end of cam follower 39 is connected with the end of the long arm of bell crank 37 and the free end of lever 34 which are slotted to allow for movement.

It will be seen that with each rotation of shaft 3, cam 38 completes a cycle. The high portion of the cam raises the follower 39, 41 and actuates lever 34 and its cam 36, removing locking pin 31 from the teeth of locking gear 30. This permits threaded shaft 18 to rotate. Simultaneously, bell crank 37 raises mounting block 16 which permits the sliding of pickup 10 to any desired location.

Where it is desired to have individual announcements or sound record 1 of more than one groove and so requiring more than one rotation of the cylinder for complete reproduction, cam 38 may be mounted on a stub shaft journaled in wall 7 and geared to shaft 3 for the proper speed ratio. That is where the individual announcement requires two rotations of cylinder 1 the gearing between shaft 3 and cam 38 is a 2:1 reduction and cam 38 rotates at half the speed of shaft 3. If n revolutions of cylinder 1 are required, then the gear reduction will be $n:1$ and shaft 3 will rotate n times to one rotation of cam 38. To allow for sidewise movement of reproducer 10 where a number of grooves is used it can be slidably mounted in arm 11 and returned to normal position under light spring or lever action. A long flexible stylus may be used to allow for such movement where needed.

Circular plate 42 is mounted on that end of sound cylinder shaft 3 journaled in wall 6 and

projecting beyond it. On that portion of plate or disk 42 which faces wall 6 and which may be referred to as the inner side are two short studs 43 and 44. Stud 43 is located about half way between the center and the outer edge of disk 42 and displaced angularly about 120° from the second stud 44 which is about one-seventh of the radius from the periphery. On the outer or opposite side of disk 42 is located a longer stud 45 which is closer to the edge of disk 42 than stud 44 and displace a few degrees from it.

Shaft 46 is pivotally mounted in projections 47 on the outer side of wall 6. At the upper end of shaft 46 and firmly fixed thereto is a V shaped member 48 of the nature of an escapement in a watch mechanism. The right arm of V member 48 has a broad inwardly projecting portion 49 which can engage stud 45. The left arm 50 of V member 48 carries a small spring pressed rod 51 having a disk 52 thereon capable of engaging stud 44 on the inner side of disk 42. As shaft 46 is rotated clockwise spring pressed rod 51 contacts disk 42 and slides through its mounting in arm 50 of member 48, compressing its spring until broad projecting portion 49 clears stud 45. When shaft 46 is rotated counter clockwise rod 51 moves toward disk 42 under the action of its spring until the stop on the end meets the arm 50. Continued rotation of shaft 46 moves rod 51 away from disk 42 until it clears stud 44. It will be noted that the relative angular displacement of studs 44 and 45 is such that they may be released one at a time by successive clockwise and counter clockwise rotations of shaft 46 and so permit disk 42 to rotate.

Translatively mounted below and back of shaft 3 in wall 6 is another spring pressed rod 53 having an enlarged head so positioned that it may engage stud 43 on disk 42. Rod 53 extends through its mounting means 54 in wall 6 and is pivotally connected with lever 55. On the inner or left side of wall 6 are projecting mountings 56 in which vertical rod 57 is pivotally mounted. Lever 55 is securely attached to the lower end of rod 57. Lever 58, having a small angular displacement relative to lever 55, is firmly fastened to the upper end so that levers 55 and 58 move as a unit with rod 57. Lever 58 extends toward threaded shaft 18 and is of sufficient length to be operated by mounting block 13 as shown in dotted lines in Fig. 2. A spring snap means 140 engages the end of lever 58 which pulls out of a slot-like space between spring means 140 and mounting means 13 as mounting means 13 moves under the action of threaded shaft 18. The tapered end of spring snap 140 permits the end of lever 58 to slip back into its former position upon the return of means 13. It will be noted that when mounting block 13 is in the dotted position shown, pin 53 projects and engages stud 43 and prevents rotation of disk 42.

On the lower end of shaft 46 is mounted a forked bar 59 which rotates the shaft as it moves to the right or left. A horizontal governor shaft 60 is mounted on the base of the device in bearings 61.

Slidably mounted on governor shaft 60 is a circular plate or disk 62 which moves to the right or left under the action of governor 63. Plate 62 carries a grooved wheel 64 in which the forks of bar 59 ride. Adjacent plate 62 and arranged to bear thereon is an adjustable speed control 65 which limits the speed of governor shaft 60.

On the end of governor shaft 60 removed from wall 6 is mounted a pinion 66 mating with gear

67 mounted on the end of shaft 68 which is journaled in bearings 69. Bevel gear 70 is mounted on the opposite end of shaft 68 from gear 67 and mates with bevel gear 71 on drive shaft 28.

On the outer end of shaft 3, beyond disk 42, is a worm gear 73 for driving the sound cylinder shaft 3.

Where, as mentioned previously it is desired to reproduce announcements requiring two or more rotations of cylinder 2 and shaft 3 it will be necessary to locate worm gear 73 between disk 42 and wall 6 and shorten shaft 3. Disk 42 will be slightly displaced and mounted on a stub shaft journaled in wall 6. The gearing ratio between shaft 3 and the stub shaft would be the number of turns of the cylinder 2 required to reproduce the announcement, i. e. N:1.

Mounted on the outer part of wall 6 are bearing projections 74 rotatively carrying vertical shaft 75 on which is mounted worm 76 engaging worm wheel 73. Worm wheel 77 is mounted on the bottom end of shaft 75.

A horizontal governor shaft 78 is journaled in bearing 79 and carries a worm 80 mating with worm wheel 77.

A circular plate or disk 81 similar to disk 62 is slidably mounted on governor shaft 78 and actuated by a weighted spring type governor 82. An adjustable speed control 83, similar to control 65, is adapted to bear on disk 81 to limit the upper value of the speed of governor shaft 78.

Governor shaft 78 carries at one end a worm 84 which mates with worm gear 85 on short vertical shaft 86 which is suitably mounted in bearings 87 and 88.

On the upper end of vertical shaft 86 is a worm 89 which mates with large free running worm wheel 90 on spring motor shaft 91. Motor shaft 91 is suitably mounted in bearings 92 and carries a ratchet wheel 93 closely adjacent free running worm wheel 90. Spring pressed pawl 94, pivotally mounted on worm gear 90, engages ratchet 93 when spring motor 95 on shaft 91 is unwinding. Spring motor 95 is mounted firmly on the base.

The other end of motor shaft 91 carries a winding gear 96 and a small Geneva wheel 97.

Two large bevel gears 98 and 99 connected by bevel pinion 100 are mounted on short shafts 101 and 102 which are in turn mounted in bearing supports 103, 104 and 105, the central bearing support 104 serving both shafts. Another winding gear 106 mating with gear 96 is mounted on shaft 101. Bevel pinion 100 is mounted on a cross-shaft 107 turning in bearing supports 104 and 108.

Running free on shaft 102 is a large worm gear 126 mating with worm 127 on drive shaft 28. A ratchet wheel 128 is mounted on shaft 102 to turn therewith. Pawl 129 mounted on worm gear 126 and pressed by spring 130 into the teeth of ratchet wheel 128 insures unidirectional rotation of gear 126 and shaft 102.

A short rod 109 is slidably supported in bearing mounting 110. Rod 109 and shaft 107 are joined by bearing 108 which permits shaft 107 to rotate and be moved in and out. In this manner the meshing of bevel pinion 100 with bevel gears 98 and 99 is determined. The reciprocating movement of rod 109 is obtained by means of small toggle bars 113 having slots 117 cooperating with pin 111 in the end of rod 109.

Small toggle bars 113 are pivoted at 114 in bifurcated mounting 115. A shaft 116 is mount-

ed in the bifurcations of member 115 and is supported at its other end in upstanding member 117. A small lever 118 is firmly mounted on shaft 116 to turn therewith and is resiliently connected to small toggle bars 113 by spring 119 attached to cross member 120 jointing the small toggle bars.

Large toggle bar 121 is firmly mounted on shaft 116 between bearing supports 115 and 117. At the upper end of mounting member 117 is pivoted a large Geneva wheel 122 having a stud 123 projecting therefrom a sufficient distance to engage in slot 124 of large toggle bar 121. Large Geneva wheel 122 mates with a small Geneva wheel 97 on motor shaft 91.

The operation of the device is as follows:

It will be noted that in the normal unoperated condition of the machine, the rise on cam 38 is uppermost, or in a position which raises cam follower 39, 41 and also the slotted ends of bell crank 37 and lever 34. Thus, initially, locking pin 34 is withdrawn and gear 30 and shaft 18 are free to turn. Also crank 37 holds rod 17 in a raised position which in turn holds the reproducer or pickup 10 and its stylus free of the cylinder 4. The reproducer 10 is therefore free to be moved along rods 15 and 17 without scratching the cylinder surface or injuring the mechanism of the reproducer.

A person to be weighed steps on the scale platform and depresses it. The platform is of conventional construction and operatively connected to drive shaft 28 by conventional rack and pinion means not shown. The movement of the platform rotates drive shaft 28 which in turn rotates shafts 25 and 18 through the gearing shown.

A certain definite rotation of threaded shaft 18 moves the reproducer 10 a certain predetermined corresponding distance along rods 15 and 17 to a place on record 1 where the desired announcement is recorded. The stylus of reproducer 10 is thus positioned just above the appropriate groove in the record 1. Flexible tubing 14 readily lends itself to such movement.

As mounting block 13 moves to the left under the action of threaded shaft 18 lever 58 is likewise moved to the left by spring snap means 140 until the end of lever 58 pulls out of the slot space under the spring as the mounting block moves farther to the left. The rotation of lever 58 in turn rotates vertical shaft 57 and lever 55.

Lever 55 draws in spring pressed rod 53 against the action of its spring so that its enlarged head no longer engages stud 43 on disk 42.

As the speed of governor 63 builds up, it rotates shaft 46 and spring pressed rod 51 with its disk 52 clear of stud 44 on disk 42. Thus spring pressed rod 51 and its disk 52 release stud 44 after enlarged portion 49 is positioned beneath stud 45. The rotation of disk 42 after this release is again checked by the action of enlarged portion 49 engaging stud 45 when disk 42 has completed its cycle.

As shown in Fig. 7 rotation of shaft 46 by action of governor 63 releases stud 44. At the same time enlarged portion 49 of V member 48 is moved over adjacent disk 42. Stud 45 has however already gone by and portion 49 does not engage stud 45 until near the completion of the cycle.

Continued rotation of disk 42, cylinder 2 and shaft 3 also rotate cam 38, lowering cam follower 39 to the long dwell. The lowering of follower 39 pivots lever 34 and bell crank 37. Lever

34 actuates locking pin 31 by means of cam 36 so that the pin 31 engages the teeth of gear 30 thus locking shaft 18 against rotation. By this time of course reproducer 10 has been located above the proper groove in record 1.

Rotation of bell crank 37 about its pivot lowers guide bar 17 and mounting block 16 so that the stylus of reproducer 10 engages the cylinder 1.

After the announcement is made the rise on cam 38 again lifts follower 39 which in turn lifts the stylus of reproducer 10 off record 1 and withdraws locking pin 31, releasing gear 30.

Control disk 42 rotates with cylinder 2 on shaft 3 and is stopped when outer stud 45 engages enlarged portion 49 of V member 48. When governor 63 ceases rotation forked member 59 and V member 48 rotate so that enlarged portion 49 is rotated clockwise (as seen from above) to release stud 45. The release of stud 45 is effected by the action of the springs which support the weights of governor 63. The action of these springs pushes bar 59 to the left when the rotation of governor 63 ceases and moves V member 48 clockwise. Stud 44 does not engage enlarged head 52 on rod 51 until disk 42 completes one revolution. Disk 42 rotates until stud 44 engages disk 52 on rod 51. At this stage this portion of the apparatus is ready for the next cycle.

When the scale platform is released and restored to its original position by the weighing mechanism, shafts 26 and 18 are rotated in a reverse direction which restores reproducer 10, sliding mounting blocks 13 and 16 on guide bars 15, 17. The end of lever 58 slips under the tapered end of spring snap means 140. Lever 58, shaft 57 and lever 55 had been previously rotated under the action of the spring surrounding rod 53 which projects and engages stud 43. Disk 42 is thus held against rotation when V member 48 is rotated by governor 63 on the return of the scale platform.

The cylinder 2 is rotated by a spring motor 95. Worm gear 73 on shaft 3 is rotated by worm 76 on shaft 75 which has a worm gear 77 on its lower end. Horizontal governor shaft 78 carries a worm 80 mating with worm gear 77 and a second worm 84 mating with worm gear 85 which is on the same shaft 86 as worm 89. The above train is driven by large worm gear 90 which runs freely on spring motor shaft 91. Since gear 90 is free running it is moved in one direction only by ratchet 93 and pawl 94. It is unaffected by the winding of spring 95.

Spring shaft 91 is turned for winding by winding gears 96, 106, shaft 101, 102 and bevel gears 98, 99 engaging pinion 100. Shaft 102 is rotated by large free running worm gear 126 mating with worm 127 on shaft 28. When gear 126 rotates clockwise pawl 129 engages ratchet 128 which is firmly attached to shaft 102. When shaft 28 reverses gear 126 merely spins freely.

Bevel pinion 100 and its shaft 107 are slidably movable so as to disengage bevel gears 98 and 99 and free that portion of the winding train. The position of pinion 100 is controlled by sliding rod 109 and toggle bars 113, 121. Large Geneva wheel 122 acting on toggle 113, 121 by means of pin 123 moves bevel pinion 100. Small Geneva wheel 97 on spring motor shaft 91 mates with large wheel 122 and makes one complete turn between the extreme positions of pin 123.

The first rotations of shaft 28 winds the spring 95 through the winding train referred to above. Spring 95 is wound by one turn of spring shaft 91. After two rotations of the spring shaft pin 123

has moved the toggle back and spring 119 disengages pinion 100 from gears 98, 99.

Spring 95 then unwinds and drives the train leading to shaft 3. The unwinding of spring 95 reverses small Geneva wheel 97 and large Geneva wheel 122. Pin 123 brings the toggles back to their former position and pinion 100 is again meshed with bevel gears 98 and 99.

The above description sets forth one embodiment of the invention and is to be regarded as illustrative and not as limiting. The concept lends itself to many adaptations. The recorded announcements could be on film if desired and picked up by a light sensitive cell.

The invention could be made more compact by placing the motor, winding device and release controls between upstanding side wall members 6 and 7. This could be accomplished by raising the record cylinder high enough to accommodate the parts and by changes in positioning the various control devices.

With regard to Geneva wheels 97, 122; toggles 113, 121; sliding shaft 109; bevel pinion 100 and bevel gear 99 it may be stated that this assembly is provided for two reasons. Otherwise shafts 101 and 102 could have been solid.

First each patron who steps on the scales will supply a certain amount of energy which is transmitted to the motor spring through the winding gear train. The force applied will not be the same for all patrons. To prevent a two hundred fifty pound person from winding the spring twice as much as a one hundred and twenty-five pound person, means had to be provided to wind the spring shaft a given amount and then automatically disengaging the winding train.

Second, means had to be provided to allow the spring shaft to unwind and drive the record cylinder while a patron still remainder on the scale platform.

I claim:

1. In a selective announcement device, a movable record having a series of recordings thereon, a reproducer mounted adjacent said record, means mounting said reproducer in operative relation to said record to reproduce said recordings from said record, means mounting said reproducer and record for relative shifting movement to selected positions relative to each other to reproduce a selected recording, drive means connected to said record to move the same, a movable control member operatively connected to said reproducer to cause said relative shifting movement to selected positions when said member is moved in one direction and means operated by said control member and operatively connected with the record to successively start and stop movement of said record when said control member is moved in said one direction.

2. The combination set forth in claim 1, said means mounting said reproducer comprising means connected to said record whereby movement thereof raises and lowers said reproducer.

3. The combination set forth in claim 1, locking means connected to said means mounting said reproducer and said means mounting said reproducer and said record for relative shifting movement whereby a portion of said reproducer is locked in said selected position during reproduction of an announcement.

4. The combination set forth in claim 1, said drive means comprising lost motion mechanism whereby excess energy is dissipated.

5. The combination set forth in claim 1, said

drive means comprising a disengaging mechanism.

6. The combination set forth in claim 1, said control member comprising a drive shaft connected to said drive means and said means mounting said reproducer and record for relative shifting movement.

7. The combination set forth in claim 1, said last mentioned means comprising a disc with lugs projecting therefrom and a pivoted member arranged to engage at least one of said lugs.

8. The combination set forth in claim 1, said control member being connected to and controlling the operation of said means mounting said reproducer and record for relative shifting movement, said drive means and said means operatively connected with the record to successively start and stop movement of said record.

9. The combination set forth in claim 1, lever means actuated by rotation of said record acting to lock said means mounting said reproducer and record for relative shifting movement during the reproduction of a selected recording.

10. The combination set forth in claim 1, said drive means comprising a spring and a winding train connecting it to said control member, means disconnecting said train when said spring is sufficiently wound.

11. The combination set forth in claim 1, said last mentioned means comprising an escapement mechanism actuated by a governor connected to said control member.
